UNITED STATES PATENT OFFICE.

HERMANN R. BOISSIER, OF NEW YORK, N. Y.

REGULATOR FOR DYNAMO-ELECTRIC MACHINES.

SPECIFICATION forming part of Letters Patent No. 408,205, dated August 6, 1889.

Application filed October 17, 1888. Serial No. 288,388. (No model.)

To all whom it may concern:

Be it known that I, HERMANN R. BOISSIER, of the city, county, and State of New York, have invented an Improvement in Regulators for Electric-Light Circuits, &c., of which the following is a specification.

My invention has reference to regulators for electric-light circuits or others having a varying resistance between the leads from the dynamo; and it consists of certain improvements which are fully set forth in the following specification, and shown in the accompanying drawings, which form part thereof.

The object of my invention is to provide automatic mechanism which shall vary the resistance in the shunt or field-coil circuit of a low-tension-current machine adapted for electric lighting or equivalent purposes. When all of the lights are in circuit, the resistance is out of circuit. When a given number of the lamps are cut out, then the line-resistance is greater, but the work required of the dynamo is less; and hence a portion of the resistance is automatically cut into the shunt or field-coil circuit. If more of the lamps are cut out, the regulator automatically puts in more resistance. In practice, on small circuits of, say, twenty-five lamps for house use, I have found two auxiliary resistances sufficient for the purpose. By employing these resistances too much current cannot be passed through the lamps when but few only are on circuit and thereby the life of the lamp be shortened.

In the drawings, Figure 1 is a general view illustrating my invention with the regulator-magnets in series with the line or leads, and Fig. 2 is a similar view when the regulator-magnets are placed in shunt relation with the leads and lamps.

40 A is the dynamo, of any suitable construction.

B is the commutator, and C C the brushes.

D is the regulator-frame, and supports three bobbins E, having each two coils of coarse wire F. Working in these bobbins or helices are three cores H H' H, supported from a bar G, hung by a head J to a switch-lever K, pivoted at L to the frame D. This lever K has a counterbalancing-weight k, working on a screw, and a spring-contact m, which plays over the contacts M M M. The lines or leads are represented by e, and include the lamps P or other

translating devices. The three coils F are in parallel circuit in one of said leads e, preferably that connecting with the positive pole of the dynamo. This arrangement makes them offer but small resistance and insures a sensitive regulator. If the regulator-coils were in series or of high resistance, they would create objectionable results when the line resistance was materially varied, and would also reduce the efficiency of the apparatus.

R is the external shunt-circuit of the field-coils, and includes the lever K. The upper contact M connects with the shunt-circuit R without interposing any resistance. The next lower contact M inserts a resistance O of, for example, five ohms, and the lower contact M inserts a resistance N of, for example, five ohms. As the lever K is shifted upward over the contacts M, it first cuts out one of the five ohms and leaves five ohms resistance, and then removes the five ohms resistance. It will be observed that the two lateral cores H are arranged considerably above the central core H', which latter may be hung on a rod I and made adjustable by a nut i or otherwise. This difference in location will make the apparatus more positive in shifting and less liable to fluctuations, and with but small movements to the cores it insures accurate movements to the lever K with given changes in the line resistance.

In the construction shown in Fig. 2 the regulator is arranged in shunt relation with the lamps P, and not in series, as before.

S is the shunt-circuit, including the coils F of the regulator, which in this case would be wound with fine wire, so as not to shunt too much current from the lamps.

If during the running of the apparatus all of the lamps are in circuit, then the lever K will rest upon the upper contact M, giving the full current to the shunt field-coils, and as the lamps are cut out the lever descends to the other contacts, first cutting in the smaller resistance and then the larger. It is clear that there may be a series of resistances to be thus cut in and out of the field-coils; but this is not necessary in a small plant with, say, twenty-five lamps.

The details may be modified without departing from my invention.

Having now described my invention, what I

claim as new, and desire to secure by Letters Patent, is—

1. The combination of a shunt-wound dynamo-electric machine, a line-circuit leading therefrom, translating devices in said line-circuit, a circuit in series with the shunt-coils of the dynamo, one or more resistances, a switch having an adjusting-weight to insert or remove said resistances in the shunt-circuit of the dynamo, and an automatic electro-magnetic regulator, consisting of two or more helices having two or more cores connected to the same support and in which one of said cores is arranged lower down into its helix than the others.
- 10 2. The combination of a shunt-wound dynamo-electric machine, a line-circuit leading therefrom, translating devices in said line-circuit, a circuit in series with the shunt-coils of the dynamo, one or more resistances, a switch to insert or remove said resistances in the shunt-circuit of the dynamo, and an automatic electro-magnetic regulator, consisting of two separate helices, and separate relatively-adjustable cores therefor connected with the switch for actuating said switch upon varying the line resistance arranged in series with the line.
- 20 3. The combination of a shunt-wound dynamo-electric machine, a line-circuit leading therefrom, translating devices in said line-circuit, a circuit in series with the shunt-coils

of the dynamo, one or more resistances, a switch to insert or remove said resistances in the shunt-circuit of the dynamo, and an automatic electro-magnetic regulator, consisting of two or more helices having two or more cores connected to the same support and in which one of said cores is arranged lower down into its helix than the others.

35

4. A regulator for a shunt-wound dynamo-electric machine and line-circuit with a varying resistance, consisting of three helices in circuit with the line, three cores therefor, one of which enters its helix to a greater extent 40 than the others, and a switch actuated by said three cores to insert or remove a resistance into or out of the shunt-circuit of the dynamo-electric machine.

45

5. A regulator for a shunt-wound dynamo-electric machine and line-circuit with a varying resistance, consisting of three low-resistance helices in parallel circuit with the line, three cores therefor, one of which enters its helix to a greater extent than the others, and 50 a switch actuated by said three cores to insert or remove a resistance into or out of the shunt-circuit of the dynamo-electric machine.

55

In testimony of which invention I hereunto set my hand.

HERMANN R. BOISSIER.
